UNITED STATES PATENT OFFICE.

FRANK S. HYATT, OF BROOKLYN, NEW YORK.

TUBE COMPRESSOR.

1,422,864.

Specification of Letters Patent. Patented July 18, 1922.

Application filed November 5, 1920. Serial No. 422,013.

To all whom it may concern:

Be it known that I, FRANK S. HYATT, a citizen of the United States, and a resident of Brooklyn, in the county of Kings and State of New York, have invented certain new and useful Improvements in Tube Compressors, of which the following is a specification.

My invention relates to clamping devices designed to apply clamping pressure to a tube or similar object and which, as usually constructed, embody an actuating cam or member mounted in a pair of ears or brackets rising from one clamping member and operating upon an upper or second clamping member arranged between the ears.

Devices of this general character and made of sheet metal are described in Letters Patent of August J. Frey No. 1,217,433 and 1,297,456 and also in the joint application for patent filed by me with the said August J. Frey on September 10, 1919, No. 322,829, allowed October 2nd 1920.

In devices of this general character the practice heretofore has been to stamp out the lower jaw or clamping member and the ears or brackets from sheet metal, the blank so formed and having the ears to be bent up in the finished construction of said prior application being illustrated in Fig. 1 of the accompanying drawings.

The object of my present invention is to permit the ears or brackets and the lower clamping member to be made of separate straight or substantially rectangular pieces of sheet metal, thereby effecting a great saving in the amount of material required since the method heretofore employed of stamping out the lower member and ears in a single irregular cross-shaped piece is exceedingly wasteful of sheet metal material.

The object of the invention is, at the same time, to properly assemble or combine the lower member and the ears so as to avoid the possibility of their becoming detached from one another.

The present invention is herein shown as applied to the particular form of tube compressor described and shown in the joint application above referred to.

Fig. 1 shows the blank embracing the lower member and the ears or brackets employed in previous constructions as cut out or struck up from a sheet of metal and previously to the bending up of the ears or brackets.

Fig. 2 shows in plan the blank for the lower member as made for the purpose of carrying out my present invention and

Fig. 3 illustrates the blank for the ears or brackets as made for the purpose of my present invention.

Fig. 4 is an end view of the blank shown in Fig. 3 after the bending of the same to form it into a stirrup.

Fig. 5 is an end elevation of the stirrup and lower clamping member assembled.

Fig. 6 is a vertical section through the same on the central line of the ears or brackets

Fig. 7 is a plan of the same parts.

Fig. 8 is a side elevation of the complete tube compressor constructed in accordance with my present invention.

1 is the lower clamping member made of a piece of sheet metal as illustrated in Fig. 2 and having clamping jaws 8 which co-operate with clamping jaws 9 upon an upper clamping member 10 properly guided and operated by the cam 3 pivoted by its pin 75 tles in the ears or uprights and provided with the operating arms 5 and 6 and the intermediate strut or brace 7 after the general manner described in the prior application before referred to.

In the previous construction the ears 2 in which the clamping jaw or cam is pivoted rise from the sides of and are integral with the sheet metal piece forming the lower clamping member 1. In my present invention the arms or ears are the sides of a piece of sheet metal like a stirrup (Fig. 4) in the foot 13 of which the clamping member 1 is supported as illustrated more particularly in the central section Fig. 6, the foot 13 underlying the body of the member 1.

As before stated, this stirrup is made from a blank as illustrated in Fig. 3, the ends of the blank being turned up and the sides given the proper curve to properly receive the tube to be clamped as shown in Fig. 4. The clamping jaw or member 1 may be anchored in the stirrup in any suitable way as by bending up part of the sheet metal of one member and interlocking it with the other member, as for instance by using a slot or slots in the member 1 and bending down the ears struck up from the metal of the member 13 and passed through said slots. Conversely, as will be readily recognized, the anchoring ears might rise from the body of the clamping member 1 support-

ed in said stirrup and pass through slots in 13.

As will be seen, the construction is as strong as the old construction of lower 5 clamping member and ears or brackets while, at the same time, the cost of production is very materially reduced.

The manner of guiding the upper clamping member on the ears or brackets may be 10 that usually employed and consisting of slots in said member through which the ears or brackets rise. Inasmuch as the lower clamping member 1 rides in the stirrup, it will be rigidly held against the strain imparted by the clamping jaw or cam when exerted upon the upper clamping member and the construction practically provides a solid 15 base and reinforcement for the lower clamping jaw which is necessarily subjected to a great strain in the operation of the device.

What I claim as my invention is:—

1. In a sheet metal compression clamp of the character described, the combination of two separate oblong pieces of sheet metal 25 disposed transversely to one another, one of said pieces being a flat piece of sheet metal constituting the lower clamping member and located wholly below the tube to be

clamped, the other piece being longer than the first and having its ends bent up to 30 form the ears for the cam operating upon a separate upper clamping member and means for securing the two sheet metal pieces together one upon the other, to form a sheet metal base of double thickness. 35

2. In compression clamp of the character described, the combination of a lower clamping member, consisting of an oblong piece of sheet metal, a second oblong piece of sheet metal of greater length than the 40 first and bent to form a stirrup in the flat base of which the first-named sheet metal member rests, one of said members being provided with slots and the other with ears passing through said slots and bent down to 45 anchor them together so as to form a base support for the tube of double thickness of sheet metal and a clamping jaw pivoted in the ends of the longer piece.

Signed at Brooklyn, in the county of 50 Kings and State of New York this 3d day of November A. D. 1920.

FRANK S. HYATT.
